(57) **CLAIM**

The ornamental design for a surgical blade, as shown and described.

DESCRIPTION

FIG. 1 is a front perspective view of a surgical blade according to a first embodiment of our design;
FIG. 2 is a front view thereof, with a rear view being a mirror image of FIG. 2;
FIG. 3 is a left side view thereof;
FIG. 4 is a right side view thereof;
FIG. 5 is a top view thereof;
FIG. 6 is a bottom view thereof;
FIG. 7 is a front perspective view of a surgical blade according to a second embodiment of our design;
FIG. 8 is a front view thereof, with a rear view being a mirror image of FIG. 8;
FIG. 9 is a left side view thereof;
FIG. 10 is a right side view thereof;
FIG. 11 is a top view thereof;
FIG. 12 is a bottom view thereof;
FIG. 13 is a front perspective view of a surgical blade according to a third embodiment of our design;

FIG. 14 is a front view thereof, with a rear view being a mirror image of FIG. 14;
FIG. 15 is a left side view thereof;
FIG. 16 is a right side view thereof;
FIG. 17 is a top view thereof;
FIG. 18 is a bottom view thereof;
FIG. 19 is a front perspective view of a surgical blade according to a fourth embodiment of our design;
FIG. 20 is a front view thereof, with a rear view being a mirror image of FIG. 20;
FIG. 21 is a left side view thereof;
FIG. 22 is a right side view thereof;
FIG. 23 is a top view thereof; and,
FIG. 24 is a bottom view thereof.
The broken lines in the drawings depict portions of the surgical blade and form no part of the claimed design.
The dash-dot lines adjacent shaded areas represent bounds of the claimed design and form no part thereof.
